UNITED STATES PATENT OFFICE.

GUSTAVE E. LUNDBERG, OF KEWANEE, ILLINOIS.

DESIGN FOR A BATTERY-CONNECTOR.

58,675.

Specification for Design.

Patented Aug. 9, 1921.

Application filed February 2, 1920. Serial No. 355,772. Term of patent 14 years.

To all whom it may concern:

Be it known that I, GUSTAVE E. LUNDBERG, a citizen of the United States, residing in the city of Kewanee, county of Henry, and State of Illinois, have invented a new, original, and ornamental Design for Battery-Connectors, of which the following is a specification, reference being had to the accompanying drawing, forming part thereof.

The figure is a view in perspective of a battery connector, showing my new design.

I claim:

The ornamental design for a battery connector, as shown.

In witness whereof, I have hereunto subscribed my name this 21st day of Jan., 1920.

GUSTAVE E. LUNDBERG.
